US00D781037S

(12) **United States Design Patent** (10) Patent No.: **US D781,037 S**
(45) Date of Patent: **** Mar. 14, 2017**

(54) **SHOE SOLE**

(71) Applicant: **Reebok International Limited**, London (GB)

(72) Inventors: **Paul Davis**, Blackstone, MA (US); **Paul Litchfield**, Westboro, MA (US); **William Marvin**, Canton, MA (US)

(73) Assignee: **Reebok International Limited**, London (GB)

(**) Term: **14 Years**

(21) Appl. No.: **29/513,350**

(22) Filed: **Dec. 30, 2014**

Related U.S. Application Data

(62) Division of application No. 29/416,617, filed on Mar. 23, 2012, now Pat. No. Des. 722,426.

(51) **LOC (10) Cl.** **02-04**

(57) **CLAIM**

The ornamental design for a shoe sole, as shown and described.

DESCRIPTION

FIG. 1 is a perspective view of a shoe sole showing the claimed design;

FIG. 2 is a right side view thereof;

FIG. 3 is a left side view thereof;

FIG. 4 is a top plan view thereof;

FIG. 5 is a bottom view thereof;

FIG. 6 is a front view thereof; and,

FIG. 7 is a rear view thereof.

The dashed broken lines in the figures show portions of the shoe and shoe sole that form no part of the claimed design.

The dot-dash broken lines in the figures show boundaries that form no part of the claimed design.

1 Claim, 6 Drawing Sheets
